Lacy Tracy Attorneys

UNITED STATES PATENT OFFICE.

EDMOND H. PALMER, OF SANFORD, FLORIDA.

EXPLOSIVE-CHARGE PLACER.

Application filed January 24, 1924. Serial No. 688,220.

To all whom it may concern:

Be it known that I, EDMOND H. PALMER, a citizen of the United States, residing at Sanford, in the county of Seminole and State of Florida, have invented certain new and useful Improvements in Explosive-Charge Placers, of which the following is a specification.

My invention relates to a device for placing an explosive charge in the ground.

Ordinarily, such charges are dropped down in a hole bored in the ground and pushed to the bottom by means of a tamping rod. This method is liable to cause tearing or injury to the cartridge and might even be the cause of serious accidents as the charge may explode prematurely.

The object of the invention is to furnish a head in which a cartridge can be placed and which head is pushed down in the ground to the correct depth by means of a long pipe. With the head and pipe thus positioned the cartridge with the ignition cap attached is dropped through the pipe and secured in the chamber formed in the head by means of a tamping rod. The head holding the charge and the ignition cap is now left in the ground and the pipe withdrawn.

In the accompanying, one embodiment of the invention is illustrated, and

Figure 1 represents an axial section of the device;

Figure 2 a transverse section along line 2—2 of Figure 1.

In the drawing, reference numeral 10 represents the explosive charge or cartridge which is usually enclosed in a bag. Reference numeral 11 represents the ignition cap placed at the upper end of the cartridge and connected with a pair of electric conductors 12 by means of which the charge is exploded.

The cartridge 10 is enclosed in a plug or head 13 preferably made of wood or similar fibrous material and having square or other polygonal cross section. The cap is pointed at its lower end, as at 14, in order to easily penetrate the ground and the sharp edges 15 of the cap are nicked to provide upwardly directed teeth or barbs. These barbs are intended to grip the ground and prevent retraction of the head after it has been inserted in the ground. The head has a chamber 16 of a size suitable to contain the cartridge 10 and at the upper end of the chamber an annular shoulder 17 is cut in the wall and concentric therewith. This shoulder 17

forms a seat for the lower end of a metallic pipe 18 which fits snugly in the seat so as to temporarily hold the head when inserted in the ground. This pipe is of sufficient length to reach up above the ground and has an inner diameter substantially the same or somewhat larger than the diameter of the chamber 16.

After the head 13 and the pipe 18 are placed in the ground, the cartridge is positioned in the chamber 16 together with the ignition cap 11 by dropping them through the pipe 18. The conductors are held on opposite sides of the tube 18 and a cylindrical disc or wad 19 is pushed down through the pipe. This wad has on opposite sides thereof a pair of longitudinal grooves 21 adapted to accommodate the conductors 12 so that the wad can be pushed down in the pipe without disturbing the conductors. To place the cartridge and wad in proper position, a tamping rod 20 is used having sufficient length to reach in from the outer end of the pipe 18 and pack the wad tightly over the cap 11 in the upper end of the cartridge 10 to retain the same in position in the head 13.

As the cartridge does not come in direct contact with the ground there is no danger of it being injured, the head being previously pushed down in the ground by hammering on the upper end of the pipe 18 until the desired depth is reached. The downward pressure from the hammering on the tube is directly communicated to the head 13 through the shoulder 17. The tamping rod 20 having been previously removed, the pipe 18 is thereupon turned in its seat 17. The square sectional shape of the head 20 will then prevent the turning of the head in the ground and after the pipe has been sufficiently loosened in its seat it may be withdrawn, leaving the head with the charge in position, the barbs or teeth 15 assisting in retaining the head in the ground, and the cap and conductors being held in the head by the wad 19. The hole in the ground can now be filled while the upper ends of the conductors 12 are connected with an electric battery and the charge exploded.

Having thus described the invention, what is claimed as new is:

1. An explosive charge placer comprising a head of polygonal cross section and provided with a cylindrical chamber adapted to receive a cartridge, a seat being formed in said head above the chamber of greater

diameter than the chamber, and a tubular member adapted to engage in the seat to carry said head, said head being provided with a pyramidal spear point at its forward end and its sharp side edges being nicked to provide rearwardly directed teeth.

2. An explosive charge placer comprising a non-metallic head of polygonal cross section and provided with a cylindrical chamber adapted to receive a cartridge, a seat being formed in the head above said chamber of greater diameter than the chamber, and a tubular member adapted to engage in the seat to carry the head, said head being provided with a pyramidal spear point at its forward end and its sharp side edges being nicked to provide rearwardly directed teeth, the bore diameter of the tubular member being substantially the same as that of said chamber and its walls having uniform thickness throughout.

3. An explosive charge placer comprising a non-metallic head of square cross section and having a cylindrical chamber adapted to receive a cartridge, an annular seat being formed in the head above the chamber of greater diameter than the chamber, a tubular member adapted to engage in the seat to carry the head, said head being provided with a pyramidal spear point at its forward end and its sharp side edges being nicked to provide rearwardly directed teeth, the bore diameter of the tubular member be-

ing substantially the same as that of said chamber and its side walls having uniform thickness throughout, and a disc fitting loosely in the bore and provided with longitudinal grooves adapted to receive electric conductors for the ignition cap of said cartridge.

4. An explosive charge placer comprising a non-metallic head of square cross section and having a cylindrical chamber adapted to receive a cartridge, an annular seat being formed in the head above the chamber of greater diameter than the chamber, a tubular member adapted to engage in the seat to carry the head, said head being provided with a pyramidal spear point at its forward end and its sharp side edges being nicked to provide rearwardly directed teeth, the bore diameter of the tubular member being substantially the same as that of said chamber and its side walls having uniform thickness throughout, a disc fitting loosely in the bore and provided with longitudinal grooves adapted to receive electric conductors for the ignition cap of said cartridge, and a tamping rod for inserting the cartridge with the ignition cap and the disc into said chamber through the bore of the tubular member, the tamping rod being detachable from the disc.

In testimony whereof I affix my signature.

EDMOND H. PALMER. [L.S.]
